Primary Examiner — Kevin K Rudzinski*Assistant Examiner* — Paul D Bohannon(74) *Attorney, Agent, or Firm* — Hauptman Ham, LLP(57) **CLAIM**

The ornamental design for a chair, as shown and described.

DESCRIPTION

FIG. 1 is a front view of a chair bearing the design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front-left perspective view thereof.

The broken lines shown in the drawings are for the purpose of illustrating portions of the chair and form no part of the claimed design.

1 Claim, 7 Drawing Sheets(56)
